UNITED STATES PATENT OFFICE.

CHRISTIAN M. COLBY, OF MINNEAPOLIS, MINNESOTA.

DISH-WASHING TOOL.

1,401,878.

Specification of Letters Patent. Patented Dec. 27, 1921.

Application filed October 18, 1920. Serial No. 417,582.

To all whom it may concern:

Be it known that I, CHRISTIAN M. COLBY, a citizen of the United States, residing at Minneapolis, in the county of Hennepin and 5 State of Minnesota, have invented certain new and useful Improvements in Dish-Washing Tools; and I do hereby declare the following to be a full, clear, and exact description of the invention, such as will 10 enable others skilled in the art to which it appertains to make and use the same.

This invention relates to a dish washing tool, or more broadly, to a cloth holding device which is adapted to readily receive 15 and retain a cloth and to form a handle by which the cloth may be used as a dish washing cloth, dust cloth, polishing cloth, etc.

As is well known, it is often undesirable to continually immerse the hands in water 20 used in washing dishes and other articles, owing to the temperature or caustic conditions of the same. It is also frequently inconvenient or undesirable to soil the hands with various polishing and cleaning materials.

On object of the invention, therefore, is 25 to provide a device, by the use of which, a cloth may be used to perform various operations and which may be immersed in various fluids without the continued immersion of the hands therein.

It is another object of the invention to 30 provide such a device by which damage or injury to the hands is avoided in working on rough or splintery surfaces.

These and other objects of the invention 35 will become apparent as the description proceeds, in connection with the accompanying drawings, wherein like reference characters 40 refer to the same parts throughout the different views; and in which—

Figure 1 is a perspective view of the holding device proper; and

Fig. 2 is, likewise, a perspective view of 45 the device, showing the washing cloth inserted therein.

Referring to Fig. 2, the dish washing tool or holding device proper is shown at A and a cloth inserted therein as B. The device 50 A comprises a handle 1 of usual and convenient form which may be made of wood, or any other suitable material, and which has a central aperture extending longitudinally thereof at one end to receive the holder 55 2. This holder 2 is arranged to be rigidly and securely carried by the handle 1 and the

handle 1 has a reduced part at the end carrying the holding tool arranged to receive the usual ferrule 3. The device 2 extends for a short distance axially from the handle 1 and is then formed into a helix 4. While stiff wire affords a convenient material in which the device 2 may be constructed, it will be understood that any other suitable material may be used. The helix 4 expands in diameter toward its outer end and the end 5 thereof is formed to project in a straight line tangential to the helix curve and is formed with a blunt point 6. The portion 5 extends substantially normal 70 to the axis of the helix.

When it is desired to use the device, a suitable cloth B is folded across the center, so that the edges and folds thereof radiate from a point located substantially at 7. The cloth is then held in one hand and the device A held with the other, and the point 7 of the cloth is inserted into the helix and turned therein. The coils of the helix act as screw threads and the cloth will be traversed upwardly therein by a turning movement, and as the helix contracts toward its upper end, the cloth will be very firmly and securely held in place therein.

The device is then ready to be used as a 85 dish washing tool, or any other convenient purpose. The cloth will be easily manipulated to wash dishes placed in hot water without it being necessary to immerse the hands in the water. By means of the projecting part 5 having the blunt point 6 thereon, the dishes may be engaged under the edges and suitably turned and moved about in the water.

If the device be used as a scrubbing device, the end 5 will be found useful in loosening and removing materials which may have become attached to the surface being cleaned.

From the above description, it will be seen 100 that the device is one which has a wide range of utility. The device can be quickly and inexpensively made and can, likewise, be readily cleaned and kept in sanitary condition. Generally stated, the invention 105 consists in the matter shown and described and set forth in the appended claims.

What I claim is:

1. A dish washing tool having in combination, a handle, a wire or rod member projecting axially therefrom and formed at some distance from the handle into a plurality of

helical coils, said member having a free end projecting in a straight line normal to the axis of the helix.

2. A dish washing tool having in combination a handle, a wire or rod member extending axially therefrom, said member being formed with a plurality of helical turns

progressively increasing in diameter away from said handle, said member having a substantially straight portion tending outward 10 of the outer end of the helix substantially tangential thereto.

In testimony whereof I affix my signature.

CHRISTIAN M. COLBY.
